UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR-COUPING.

1,279,709.

Specification of Letters Patent. Patented Sept. 24, 1918.

Application filed December 3, 1917. Serial No. 205,100.

To all whom it may concern:

Be it known that I, WILLIAM KELSO, a citizen of the United States, residing at Pittsburgh, in the county of Allegheny and 5 State of Pennsylvania, have invented certain new and useful Improvements in Car-Couplings; and I do hereby declare the following to be a full, clear, and exact description of the invention, such as will enable 10 others skilled in the art to which it appertains to make and use the same.

My invention relates to the construction of car couplers of the type employing a pivoted knuckle. The primary objects of the 15 invention are to produce an efficient coupler mechanism in which the several parts are strong and of simple form, easily operated, and capable of facile assembly and disassembly. Generally stated, these several objects are effected by embodying in the 20 coupler certain structural features which are so correlated that they mutually coöperate to preserve the assembled relations of the elements in their various working positions and contribute to the ease of operation 25 of the mechanism.

In the drawings illustrating my invention, the scope whereof is pointed out in the claims,

30 Figure 1 is a plan view of a car coupler embodying my invention, the rear end of the coupler stem being omitted.

Fig. 2 is a view corresponding to Fig. 1, but having a portion of the upper wall of 35 the coupler head broken away to disclose the elements of the coupler mechanism within the coupler head.

Fig. 3 is a front elevation of the coupler, a portion of the knuckle being broken away 40 in order to disclose the locking mechanism more fully.

Fig. 4 is a side elevation of the coupler, a portion of the coupler head being broken away to show the interior mechanism.

45 Fig. 5 is a detail view, partly in elevation and partly in vertical section, illustrating the working parts of the coupler in their locked relation.

Fig. 6 is a view corresponding to Fig. 5, 50 but showing the positions of the parts when the lock is in lock-set position.

Fig. 7 is a view also corresponding to Fig. 5 but illustrating the positions assumed by the parts when the knuckle has released the

lock from the lock-set position shown in 55 Fig. 6.

Fig. 8 is a detail view showing the guideway for the lock on the guard arm side of the coupler head.

Fig. 9 is a view illustrating the manner 60 of assembling the knuckle opener in the coupler head.

Fig. 10 is a detail view, partly in plan and partly in horizontal section, illustrating the manner of assembling the locking mech- 65 anism in the coupler head.

Fig. 11 is a detail rear elevation of the 70 coupler lock and its associated lock-set and lock-to-the-lock mechanism.

Fig. 12 is a detail side elevation of the 70 parts shown in Fig. 11.

In the drawings, the coupler head is indicated by the reference numeral 1, and 2 is the knuckle pivotally connected to the coupler head by means of a knuckle pin 3 in the 75 usual manner. The knuckle is normally prevented from rotating to open position by means of a lock 4 which is slidably mounted within the coupler head so as to return to locked position under the influence of grav- 80 ity. The side of the lock facing the guard arm of the coupler preferably projects into a vertically extending guideway or channel 5 in the coupler head, while the side of the lock which is near the knuckle 2 is adapted 85 to coöperate with the longitudinally extending vertical face of the guide rib 6 cast on the interior of the coupler head 1. Near its lower end the guide rib 6 is interrupted or cut away, as indicated at 7 and 8, leaving 90 a lug 9. The rear corner of the lock 4 toward the knuckle side of the coupler is formed with a groove 10 corresponding to the lug 9, the portions 11 and 12 of said 95 lock above and below the groove 10 being respectively adapted to enter and turn in the corresponding recesses or grooves 7 and 8 in the guide rib 6 of the coupler head.

This construction permits the lock 4 to be brought into assembled relation with the 100 coupler head 1 by entering it in the guideway 5 and then rotating it on a vertical axis until the lug 9 has passed through the groove or channel 10 of the lock and the projecting portions 11 and 12 of the latter 105 have passed through the grooves 7 and 8 of the guide rib 6. When in coupled relation the knuckle 2 prevents the lock 4 from ro-

tating, or twisting in a direction allowing it to become disassembled from the coupler head; and the supporting shelf or seat 13 on which the lock 4 rests when in coupled 5 position may be at such an elevation that the lug portion 11 of the lock will be out of alinement with the corresponding groove 7 through the guide rib 6 when the parts are in locked position, thus allowing the portion 10 11 of the lock to overlap the lug 9, thereby also serving to prevent the lock 4 from rotating in a direction necessary to effect its disassembly from the coupler head.

The lock 4 is preferably provided with a 15 chamber or recess 14 (see Fig. 5) within which is movably mounted a member 15 that is adapted to coöperate with the coupler head 1 in two different positions, in one position (see Fig. 6) serving to maintain the lock 4 20 in elevated or lock-set position permitting a subsequent unlocking rotation of the knuckle 2, and in the other position (see Fig. 5) preventing the lock from accidentally moving to unlocked position. This member 15 is 25 preferably connected to the lock 4 by means of a pivot pin 16, being pivoted at one side of its center of gravity. It is provided with two projections 17 and 18 respectively, which are adapted to extend laterally beyond the 30 lock 4 into the recess or notch between the shoulders 19 and 20 of the coupler head. The lower projection, 17, is adapted to rest upon the lock-set seat or shoulder 19 on the guard arm side of the coupler head to support the lock in lock-set position, as illustrated in Fig. 6. Under the influence of gravity the upper shoulder or projection 18 assumes a position beneath the lug or shoulder 20 upon the coupler head when the parts 35 are in locked position, thus preventing the lock 4 from accidentally moving upward to unlocked position. The under surface of the lug 20 is preferably inclined, as shown, in order to permit the portion 18 of the pivoted member 15 to clear it freely when moved by the lifter member 21 in the act of raising the lock 4 to unlocked position. The coupler is grooved or cut away, as at 22, to allow for the movement of the lower end of the pivoted member 15 when the latter is rotated 40 with respect to the lock in the operation of unlocking the coupler. The lug or shoulder 20 is at one side of the path of movement of the lower end 17 of the member 15, thus 45 permitting the latter to clear it when the lock 4 executes the extended unlocking movement necessary to actuate the knuckle opener lever 23. By employing a pin 16 as the means for suspending the lock 4 from the member 15 ease and certainty of operation of the lock in unlocking the knuckle are insured and undue friction and binding of the lock against the coupler head are prevented; and by so positioning the pin 16 50 that the point of attachment of the lifter 21

to the member 15 is out of vertical alinement with the pin when the parts are in locked relation, prompt and positive operation of the member 15 is insured as the lifter is actuated to unlock the coupler. 70

The lifter member 21 is preferably provided at its lower end with a hook 24 which is adapted to coöperate with an eye 25 with which the member 15 is provided at its upper end. The eye 25 is formed with a 75 portion 26 of sufficiently small diameter to enter the mouth 27 of the hook, the remainder of the eye being of sufficiently large diameter to prevent the escape of the hook from the eye. This construction eliminates 80 all possibility of accidental dissociation of the pivoted member 15 and lever 21 when the parts are assembled in working relation. The lifter 21 projects upwardly through an aperture 28 in the upper wall 85 of the coupler head 1. This aperture is preferably in the form of a cross, one of its arms being adapted to receive the lifter 21 and its other arm accommodating the upper end of the eye 25 when the locking mechanism 90 is raised to its fullest extent.

The knuckle opening lever 23 is provided with oppositely disposed trunnions 29 and 30 forming means whereby the lever 23 is pivotally mounted upon the coupler head. 95 The coupler head 1 has pockets 31 and 32 which respectively receive the trunnions 29 and 30. As shown more particularly in Figs. 2 and 9, the pockets or bearings 31 and 32 are so formed that the lever 23 may be 100 rotated about a vertical axis in assembling it with or disassembling it from the coupler head 1. The upper portion of the lock 4 is provided with a shoulder 33 which is adapted to engage the short arm 34 of the knuckle 105 opener lever when the lock has been raised sufficiently to permit the knuckle to rotate to open position. The further or extended unlocking movement of the lock 4 while in engagement with the short arm of the knuckle 110 opening lever 23 causes the latter to rotate thus forcing the long arm 35 of the lever to press against the outer face of the tail of the knuckle 2, thereby rotating the knuckle to open position. In order to reduce friction 115 between the lock 4 and knuckle opening lever 23, the under face of the end of the short arm 34 of the lever is, as shown, preferably formed as a curved bearing surface; and to prevent reduction in leverage the 120 underside of the short arm 34 of the knuckle opening lever is preferably recessed, as at 36, in order to prevent the lock 4 from contacting the knuckle opening lever adjacent the trunnions 29 on which the knuckle 125 opener 23 turns. At the rear end of its tail the knuckle 2 is provided with inclined means, preferably in the form of a rib 37, for coöoperating with the lock 4 to release the latter from its lock-set position upon the 130

opening of the knuckle. The under surface of the lock 4 is preferably inclined, as indicated at 38, to coöperate with the inclined rib 37 on the tail of the knuckle.

5 In assembling the coupler the knuckle opening lever 23 is first put in place by entering its rear trunnion 30 in the pocket 32 of the coupler head and then turning the lever on a vertical axis until its front trunnion 29 is seated in the corresponding bearing pocket 31. The lock 4 with the pivoted member 15 and lifter 21 attached is next inserted, being entered through the mouth of the coupler head and brought into assembled relation with the guideway 5 and guide rib 6 as heretofore described. The knuckle 2 and the knuckle pin 3 are then put in place, thus completing the assembly of the mechanism. When the parts are in 10 locked position the contact of the long arm 35 of the knuckle opener 23 with the back of the knuckle 2 prevents accidental dislocation of the knuckle opener, and when in open position accidental displacement of the 15 knuckle opener is prevented by the contact of the short arm 34 of the knuckle opener with the shoulder 33 of the lock 4. The knuckle 2 in conjunction with the guide rib 6 prevents the lock 4 from twisting when in locked position, and the guide rib 6 upon the 20 interior of the coupler head 1 prevents twisting of the lock when the latter is in unlocked position.

When the parts are in locked position and 25 the lifter 21 is pulled upwardly the pivoted member 15 mounted upon the lock 4 is rotated upon its pivot pin 16 until its upper locking lug or projection 18 is moved from under the shoulder or lug 20 upon the coupler 30 head. The lock 4, being then free to move upwardly, is raised by the lifter 21 until it is high enough to permit the knuckle 2 to rotate outwardly. At this time the lower end 17 of the member 15 moves into position 35 vertically above the lock-set seat 19 upon the coupler head 1, so that if the upward pull upon the lifter 21 be released the lock 4 will be sustained in unlocked position through the intervention of the attached pivoted member 15, as illustrated in Fig. 6. When 40 the knuckle 2 rotates outwardly after the parts have been brought to lock-set position, as shown in Fig. 6, the inclined rib 37 upon the tail of the knuckle engages the inclined 45 lower surface 38 of the lock 4, causing the lock to be raised sufficiently to permit the lower end 17 of the pivoted member 15 to disengage and swing clear from the lock-set seat 19, the lock being then supported upon 50 the tail of the knuckle, as shown in Fig. 7. Upon the subsequent closing of the knuckle 2 the lock drops to locked position and the pivoted member 15 rotates under the influence of gravity until its shoulder or lug 55 18 stands beneath the shoulder 20 upon the

coupler head, the lock 4 being thus locked against an accidental unlocking movement. When the knuckle 2 is free to rotate outwardly an extended upward pull upon the lifter 21 causes the shoulder 33 upon the 70 lock to engage the short arm 34 of the knuckle opener 23 and rotate said knuckle opener, thus causing its long arm 35 to press against the tail of the knuckle 2 and rotate the latter upon its pivot pin 3. 75

I claim:

1. In a car coupler, the combination with a coupler head having oppositely opening pockets forming pivotal bearings for a knuckle opening device, of a knuckle pivotally mounted in said bearing pockets of the coupler head, a lock for said knuckle, and a knuckle opening device movably mounted upon said coupler head, said lock being adapted to actuate said knuckle opening device and constituting means for preventing the knuckle opening device from being dissociated from said coupler head when the knuckle is in open position. 85

2. In a car coupler, the combination with the coupler head, of a knuckle pivotally mounted thereon, a lock for said knuckle, a knuckle opening lever adapted to be actuated by said lock, and a rigid lifter member movably connected to said lock and extending upwardly to the rear of said knuckle opening lever, said lever being provided with trunnions whereby it is pivotally mounted on said coupler head, and said coupler head being formed with pockets adapted to receive said trunnions, said pockets permitting the upper arm of said lever to be rotated rearwardly about a vertical axis in disassembling it from said coupler head. 95

3. In a car coupler, the combination with the coupler head, of a knuckle pivotally mounted thereon, a lock for said knuckle, and means pivotally connected to said lock and adapted to engage said coupler head in a plurality of positions, said means when 100 in one position of engagement with the coupler head maintaining said lock in lock-set position and when in another position of engagement with said head serving to prevent said lock from accidentally moving to unlocked position. 110

4. In a car coupler, the combination with the coupler head, of a knuckle pivotally mounted thereon, a lock for said knuckle, a member pivotally mounted on said lock, and a member adapted to actuate said pivoted member, said pivoted member being pivoted at one side of its center of gravity and being adapted to engage said coupler head in one position to maintain said lock in lock-set position and to engage said coupler head in another position to prevent said lock from accidentally moving to unlocked position, and said actuating member being adapted to effect a rotation of said pivoted member on 125 130

its pivot in a direction contrary to that effected by gravity.

5. In a car coupler, the combination with the coupler head, of a knuckle pivotally mounted thereon, a lock for said knuckle, said lock being provided with a pin, a member which is movably mounted on said pin and is adapted to move by gravity into engagement with said head to thereby prevent 10 said lock from accidentally moving to unlocked position and is also adapted to engage said head to maintain said lock in lock-set position, and means for moving said last named member from the position in which it prevents the lock from moving to unlocked position to the position in which it maintains said lock in lock-set position, said means being out of vertical alinement with 15 said pin when the parts are in locked relation.
6. In a car coupler, the combination with a coupler head having a guide rib interrupted to form a plurality of grooves and an intervening lug, of a knuckle pivotally 20 mounted on said head, and a slidable lock for said knuckle, said lock being insertible into said head through the mouth thereof 25

and being provided with a groove adapted to permit the passage of said lug, and said knuckle constituting means for preventing 30 said lock from being dissociated from said head.

7. In a car coupler, the combination with the coupler head, of a knuckle pivotally mounted thereon, and a lock for said knuckle, said head being provided with guides co-operating with said lock, and one of said guides being interrupted intermediate of its ends to permit said lock to be removed from 35 said coupler head.

8. In a car coupler, the combination with the coupler head, of a knuckle pivotally mounted thereon, a lock for said knuckle, and means for preventing the lock from accidentally moving to unlocked position and 40 for maintaining said lock in lock-set position, said means involving a recess formed in said coupler head and having lower and upper surfaces which serve respectively in lock-setting said lock and in locking it 45 against accidental unlocking.

In testimony whereof I affix my signature.

WILLIAM KELSO.
